ABSTRACT

An electronic musical instrument includes an automatic accompaniment device for automatically playing bass tones properly determined for the chords being played. A chord detector tells what chord is now being played. Responsive to the chord detection, a dc voltage generator generates a dc voltage representing the bass tone to be played. The dc voltage is supplied to a voltage controlled variable frequency oscillator which generates a bass tone signal having a frequency determined by the dc voltage. Thus produced bass tone is automatically gated by a tone gate in accordance with a rhythm pattern pulse generated by a rhythm pattern pulse generator.

FIG. 6

AUTOMATIC ACCOMPANIMENT DEVICE OF AN ELECTRONIC MUSICAL INSTRUMENT

BACKGROUND OF THE INVENTION

The present invention relates generally to an electronic musical instrument and more particularly to a new and advanced automatic accompaniment device for automatically playing bass tones proper for the chords being played on the electronic musical instrument.

In general, it is customary and desirable in a musical performance effect on a musical instrument that a performer plays not only a melody but also a chord and bass accompaniment on the musical instrument. However, such a performance, particularly of basses, is difficult for a beginner.

Accordingly, in an electronic musical instrument of known type, an automatic accompaniment device comprising a circuit such as that shown in FIG. 1 has been provided. In this circuit, the operation of keyboard switches K causes one of AND circuits AND₁₁, AND₁₂ . . . to operate, and the output from the particular AND circuit is applied to AND circuits AND₂₁, AND₂₂ . . . thereby to derive proper bass tone signals out of the tone signals from bass tone generators BS to meet the chords being played. Then, the bass tone signals thus selected are applied to tone gates G₁, G₂ . . . , where the signals thus applied are gated in accordance with the signals from a rhythm pattern pulse generator RP and finally reach an output terminal O₁.

When keys C, E and G are depressed, the key switches K of C, E and G are closed and a logical product condition is established in the AND circuit AND₁₁, as a result of which the output of the AND circuit AND₁₁ is applied to the AND circuits AND₂₁ and AND₂₂. As a result, the AND circuit AND₂₁ passes a bass tone signal of C from the bass tone generator BS to the tone gate G₁, while the AND circuit AND₂₂ passes a bass tone signal of G to the tone gate G₂. The tone gates G₁ and G₂ are controlled by signals from the rhythm pattern pulse generator RP whereby the bass tone signals of the root note C and the fifth note G are applied to the output terminal O₁, respectively, at a time 1 and a time 3 according to the predetermined rhythm pattern.

On the other hand, the rhythm pattern pulse generator RP applies its signal to a tone gate G_c, whereby the tone signals of C, E and G which have been supplied from chord tone generators CS through key switches K of C, E and G are delivered to an output terminal O₂ at a time 2 and a time 4. The outputs thus obtained at the output terminals O₁ and O₂ are then audibly produced through respective amplifiers and a loudspeaker. Thus, the performer can play a melody accompanied by chords and basses, that is, even a beginner can perform an intricate musical piece.

However, since the above described conventional circuit is inevitably provided with bass tone generators including a number of tone generators in correspondence to the number of musical scale tones used, the circuit tends to be considerably complicated, and the cost of manufacturing a musical instrument having such a complicated circuit will be high.

SUMMARY OF THE INVENTION

Accordingly, a first object of the present invention is

to provide a new automatic accompaniment playing device of an electronic musical instrument in which all of the above described drawbacks accompanying the conventional device are eliminated.

5 A second object of the present invention is to provide a novel automatic accompaniment playing device of an electronic musical instrument in which a bass accompaniment is produced merely by the depressing of the keys that correspond to the component notes of a chord to be produced, and, therefore, even a beginner can obtain a good result in a complicate performance on the electronic musical instrument.

10 A third object of the present invention is to provide a new automatic accompaniment playing device of an electronic musical instrument in which bass tone generators of a type which is found in a conventional accompaniment device is eliminated whereby the new device is made much simpler in construction.

15 A fourth object of the present invention is to provide an automatic accompaniment device of an electronic musical instrument which is simplified in its entire organization, and is therefore appreciably advantageous in cost and manufacture.

20 The foregoing objects and other objects of the present invention will become more apparent from the following detailed description and the appended claims when read in conjunction with the accompanying drawings.

BRIEF DESCRIPTION OF THE DRAWINGS

In the accompanying drawings:

FIG. 1 is a block diagram illustrating a conventional automatic accompaniment playing device of an electronic musical instrument;

25 FIG. 2 is a block diagram showing a generic construction of the present invention;

FIG. 3 is a block diagram showing one embodiment of the present invention;

30 FIG. 4 is a circuit diagram illustrating a more specific example of the oscillator shown in FIG. 3;

FIG. 5 is also a block diagram illustrating another embodiment of the present invention;

35 FIG. 6 is a block diagram showing a further embodiment of the present invention; and

FIG. 7 is a circuit diagram showing in detail a control voltage generator included in FIG. 6.

DETAILED DESCRIPTION OF THE INVENTION

As shown in FIG. 2, the automatic accompanying device according to this invention comprises: a chord detector CD for detecting a chord being played, a dc voltage generator VG connected to the chord detector CD and generating a dc voltage representing a bass tone proper for the detected chord, a voltage controlled variable frequency oscillator VFO connected to the dc voltage generator VG and oscillating a bass tone signal of a frequency determined by the dc voltage, a rhythm pattern pulse generator RP for generating pulses of predetermined rhythm patterns, and a tone gate TG connected to the oscillator VFO and the pulse generator RP for gating the bass tone signal in response to the pulses.

With reference now to FIGS. 3 and 4 there is shown one example of the automatic accompaniment playing device according to the present invention. This example comprises: a chord detector including key switches K for every note (only C, E, G, F and A are shown

though) and AND circuits AND_{11} , AND_{12} . . . , each of which carries out its logical operation by the actuation of the connected key switches; AND circuits AND_{21} , AND_{22} . . . which carry out their logical operations between the outputs of the AND circuits AND_{11} , AND_{12} . . . and the outputs of a rhythm pattern pulse generator RP; a dc voltage generator including relays CX, GX . . . which are activated by the outputs of the AND circuits AND_{21} , AND_{22} . . . and a resistor R on which several intermediate terminals (taps) are provided at predetermined intervals, whereby dc voltages of various values are obtained at the intermediate terminals when a dc current flows through the resistor R; a voltage controlled variable frequency oscillator VFO which, when a voltage is applied through the closed relay contact from the resistor R to the oscillator, serves to generate a bass tone signal whose frequency is determined by the dc voltage thus applied; a tone gate G_o which gates the output of the oscillator VFO in accordance with the rhythm pattern pulses which are applied to the tone gate G_o through an OR circuit OR from the rhythm pattern pulse generator RP; and chord tone generators CS whose output are fed through key switches K to the tone gate G_c which receives a rhythm pattern pulses from the rhythm pattern pulse generator RP and gates the chord tone signals in accordance therewith.

When the key switches K of the notes C, E and G (constituting a chord of C) are closed, the logical product of the AND circuit AND_{11} is established thereby indicating that the depressed chord is 'C' and its output being fed to the AND circuits AND_{21} and AND_{23} . The AND circuit AND_{21} is provided for the root note C of the chord 'C' while the AND circuit AND_{23} is provided for the fifth note G of the same chord. The AND circuits AND_{21} and AND_{23} receive the signal from the AND circuit AND_{11} and the rhythm pattern pulses from the rhythm pattern pulse generator RP. The player of the electronic musical instrument provided with the above described device can be informed of the progression of the rhythm if for instance an indicator lamp is provided near the keyboard for facilitating the performance.

The rhythm pattern pulses are fed firstly to the AND circuit AND_{21} from an output terminal 1 of the rhythm pattern pulse generator RP, secondly to the tone gate G_c from an output terminal 2 of the generator RP, thirdly to the AND circuit AND_{23} from an output terminal 3 of the generator RP, and finally to the tone gate G_c from an output terminal 4 of the generator RP. Therefore, the AND circuit AND_{21} is first activated thereby to energize the relay CX, as a result of which the contact of the relay CX is closed. Since the contact is connected to one of the intermediate terminals of the resistor type voltage divider R, a predetermined dc voltage representing a bass tone C is available at the intermediate tap. The dc voltage is applied, as a control signal, to the voltage controlled variable frequency oscillator VFO. As a result, the oscillator VFO generates a tone signal of a frequency for the bass note C (root for the chord C). Similarly, generation of the rhythm pattern pulse at the output terminal 3 of the rhythm pattern pulse generator RP activates the AND circuit AND_{23} thereby to close the contact of the relay GX, as a result of which a dc voltage representing a bass note G is applied to the oscillator VFO from another terminal of the resistor R and the oscillator VFO in turn pro-

duces a tone signal of a frequency for the bass note G (fifth for the chord C). This signal is applied to the tone gate G_o .

As is indicated in FIG. 4, the oscillator may be, for instance, a combination of an astable multivibrator and a voltage amplifying circuit consisting of a Darlington-connected transistors Q_1 and Q_2 . In this oscillator, its oscillating frequency is varied according to the variation of the voltage applied to a control terminal V.

Referring to FIG. 3 again, the tone signals of the root note C and the fifth note G are derived from the output terminal O_1 in accordance with the operation of the tone gate G_o .

On the other hand, since the rhythm pattern pulses are fed to the tone gate G_c from the output terminals 2 and 4 of the rhythm pattern pulse generator RP, the chord signals delivered from the chord tone generators CS by depressing the keys C, E, and G is gated at the tone gate G_c . As a result, the chord note (C, E, G) signals are applied to at the output terminal O_2 .

Thus, the performer can produce from the electronic musical instrument the root bass note, the fifth bass note, and chord notes beating at the predetermined rhythm, merely by depressing the keys C, E, and G. The rhythms composed of these tones can be optionally selected by rearranging the rhythm pattern pulses from the rhythm pattern pulse generator RP.

In FIG. 5 there is shown another embodiment of the automatic accompaniment device according to the present invention, in which a pair of voltage controlled oscillators, the oscillating frequencies of which are in a certain ratio, are used as bass tone generators. In this example, two bass tone signals having predetermined frequencies are produced by the operation of keys, and the signals thus produced are gated, at tone gates, with the rhythm pattern pulses from the rhythm pattern pulse generator, so as to produce a desired bass accompaniment to the performance of a melody.

The device shown in FIG. 5 comprises: a chord detector including key switches K for every note (only C, E, G, A and F are shown though) and AND circuits AND_{11} , AND_{12} . . . whose logical operations are carried out by the actuation of the connected key switches; a dc voltage generation including relays CX, FX . . . which are activated by the operation of the AND circuits AND_{11} , AND_{12} , as a result of which the contacts of the relays are closed, and a resistor R on which several intermediate terminals (taps) are provided at predetermined intervals, whereby the dc voltages of various values are obtained at the terminals when a dc current flows through the resistor R; voltage controlled variable frequency oscillators VFO_1 and VFO_2 each of which, when a voltage is applied to it from the resistor R through the closed relay contact, generates a bass tone signal whose frequency is determined by the thus applied dc voltage, the ratio of the two frequencies oscillated by the oscillators being 2:3; and a rhythm pattern pulse generator RP. The rhythm pattern pulse generator RP is preferably such that it indicates the progression of the rhythm with the aid of, for instance, an indicator lamp which is provided near the keyboard of the electronic musical instrument so that the instrument player can operate the keys, referring to the indication of the lamp. The above described device further comprises: tone gates G_1 and G_2 which are operated by the pulses from the rhythm pattern pulse generator RP so as to gate the bass tone signal outputs from the oscil-

lators VFO₁ and VFO₂; and a tone gate G_c which is operated by the outputs of the rhythm pattern pulse generator RP thereby to gate the chord tone signals delivered to the tone gate G_c from the chord tone generators CS through the key switches K.

The circuit shown in FIG. 4 can be employed as the oscillators VFO₁ and VFO₂. As is apparent from the description set forth with reference to FIG. 4, the circuit comprises an astable multivibrator composed of transistors Q₃ and Q₄ and a voltage amplifying circuit composed of transistors Q₁ and Q₂. In the oscillator, its oscillating frequency is varied according to the value of the dc voltage which is applied to the voltage input terminal V, and output of the oscillating frequency thus varied is applied to the output terminal OUT of the circuit.

When the key switches K of the notes C, E, and G (constituting a chord of C) are closed, the AND circuit AND₁ is activated as a result of which the relay CX is energized, and a predetermined voltage is then obtained at the resistor R. The voltage thus obtained is applied to the oscillators VFO₁ and VFO₂, which in turn produce bass tone signals having frequencies determined by the dc voltage applied. In this connection, it should be noted that the ratio of the frequency of the oscillator VFO₁ to the frequency of the oscillator VFO₂ is 2:3, that is, the ratio showing a relationship between a root note and a fifth note. In this example, since the root note is C and the fifth note is G, the bass tone signals generated by the oscillators have frequencies of the C note and the G note, respectively.

The outputs of the oscillators VFO₁ and VFO₂ are applied to the tone gates G₁ and G₂, respectively, and the tone gates G₁ and G₂ in turn carry out their gating operations according to the rhythm pattern pulses which are delivered from the output terminals 1 and 3 of the rhythm pattern pulse generator RP, respectively. As a result, first, the bass tone signal of the note C is delivered to an output terminal O₁, and then the bass tone signal of the note G is delivered to the same terminal O₁.

On the other hand, the rhythm pattern pulses from the terminals 2 and 4 of the rhythm pattern pulse generator RP are supplied to the tone gate G_c, and the rhythm pattern pulses thus supplied gate, at the tone gate G_c, the chord tone signals which are delivered to the tone gate G_c through the key switches K, and as a result the tone signals constituting the chord (C, E, G) appear at another output terminal O₂.

Thus, the performer can produce the root bass note, the fifth bass note, and chord notes beating in the predetermined rhythm merely by depressing the key C, E and G. The rhythms composed of these tones can be optionally selected by rearranging the rhythm patterns of the rhythm pattern pulse generator RP.

With reference to FIGS. 6, there is shown a further example of the automatic accompaniment device according to the present invention, which also comprises a voltage controlled oscillator. In this example, two dc voltages respectively representing the frequencies for a root note and a fifth note are obtained by the operation of key switches, the thus obtained dc voltages are selectively applied to the oscillator according to the rhythm pattern pulses delivered from the rhythm pattern pulse generator thereby to produce the bass tone signals of the root note and the fifth note, and chord tone signals are also gated by the rhythm pattern pulses. Thus, a de-

sired bass and chord accompaniment is effected together with the performance of a melody.

More specifically, the example shown in FIG. 6 comprises: a chord detector including key switches K for every note (only C, E and G are shown though) and AND circuits AND₁₁ . . . which carries out its logical operation according to the operation of the connected key switches K; a dc voltage generator including relays CX, . . . each of which is energized by the operation of the AND circuits AND₁₁ . . . whereby the contacts of the corresponding relay are closed, and a resistor R on which several intermediate terminals (taps) are provided at predetermined intervals, whereby the dc voltages of various values are obtained at the terminals when a current flows through the resistor R; and a rhythm pattern pulse generator RP.

This rhythm pattern pulse generator RP is preferably such that it can indicate the progression of the rhythm with the aid of, for instance, an indicator lamp which is provided in the vicinity of the keyboard of the electronic musical instrument so that the instrument player can operate the keys, referring to the indication of the lamps.

The above described, example further comprises: dc voltage gates CG₁ and CG₂ which carry out their gating operations according to the rhythm pattern pulses delivered from the rhythm pattern pulse generator RP thereby to selectively draw out the dc voltages from the resistor R; a voltage controlled variable frequency oscillator VFO which serves to generate the bass tone signal of a frequency determined by the dc voltages selectively delivered through the dc voltage gates CG₁ and CG₂; a tone gate G_c the gating operation of which is caused by rhythm pattern pulses which are delivered through an OR circuit OR from the rhythm pattern pulse generator RP, whereby the bass tone signals from the oscillator VFO are supplied to an output terminal O₁; and a tone gate G_c the gating operation of which is caused by other rhythm pattern pulses from the rhythm pattern pulse generator RP thereby to gate the chord tone signals which are delivered to the tone gate G_c through the closed key switches K from the chord tone generators CS and to send the chord tone signals thus gated to another output terminal O₂.

The dc voltage generator, which is a part of FIG. 6, including the resistor R and the relay contacts, and serving to obtain the voltages to be used for determining the frequency of the oscillator VFO, is further illustrated in detail in FIG. 7. When a current flows through the resistor R from a d.c. source, it produces at the intermediate terminals of the resistor R the voltages that are preselected suitable for determining the frequency of the oscillator VFO. The resistor R is provided with two groups of terminals, namely, one group of terminals going to the dc voltage gate CG₁ and the other group of terminals going to the dc voltage gate CG₂. Therefore, the voltages produced at the terminals are applied to the oscillator VFO through the dc voltage gate CG₁ or CG₂.

The circuit shown in FIG. 4 can be employed as one example of the oscillator VFO. As is described before, the circuit has a voltage amplifying circuit comprising the transistors Q₁ and Q₂ and an astable multivibrator comprising the transistors Q₃ and Q₄.

When the key switches K of the notes C, E, and G (constituting chord of C) are closed, the AND circuit AND₁₁ is caused to carry out its logical operation, as a

result of which the relay CX is energized thereby to close its contacts for C and G representing voltages. Owing to these contact closures, the different dc voltages for the root note C and the fifth note G are applied to the gates CG₁ and CG₂, respectively.

The gate CG₁ and CG₂ carry out their gating operations with rhythm pattern pulses applied from the rhythm pattern pulse generator RP to them. First, the gate CG₁ is opened by the rhythm pattern pulse arriving from a terminal 1 of the rhythm pattern pulse generator RP. At a predetermined time interval thereafter, the gate CG₂ is opened by a rhythm pattern pulse arriving from another terminal 3 of the rhythm pattern pulse generator RP. Accordingly, the variable frequency oscillator VFO first receives a dc voltage which has a 15 value to produce the root note C, thereby to generate the bass tone signal of the note C, and next receives another dc voltage which has a value to produce the fifth note G, thereby to generate the bass tone signal of the note G.

The bass tone signals thus generated are applied to the tone gate G_o. The gate G_o in turn carries out its gating operation according to the rhythm pattern pulses from the rhythm pattern pulse generator RP, and owing to this gating operation, the bass tone signals from the oscillator VFO is applied to the output terminal O₁.

On the other hand, the rhythm pattern pulses from the other output terminals 2 and 4 of the rhythm pattern pulse generator RP are applied to the tone gate G_c, as a result of which the gate G_c is opened at time points 2 and 4. This means that the chord tone signals are delivered to the output terminal O₂ through the key switches K from the chord tone generators CS.

Thus, the performer can produce the root bass note, the fifth bass note, and the chord notes at predetermined rhythms, merely by depressing the keys C, E, and G. The rhythms composed of these tones can be optionally selected by rearranging a rhythm patterns of the rhythm pattern pulse generator RP.

While a few embodiments of the present invention have been illustrated and described in detail, it is particularly understood the present invention is not limited thereto or thereby.

I claim:

1. In an electronic musical instrument having a plurality of key switches wherein actuation of each key switch acts to generate a different single note of a musical scale, and automatic accompanying device therefor, said device comprising:

a voltage means, said key switches being connected to said voltage means;

chord detector means coupled to said individual key switches for monitoring designated combinations of notes being played to detect the presence of different chords, said chord detecting means comprising a plurality of AND circuits connected to said key switches as chord detecting logics, said chord detector means providing an output indicative of said selected chord;

a D.C. voltage generator means coupled to said chord detector means for generating a D.C. voltage having a level representative of said detected chord, said D.C. voltage generator comprising a source of D.C. current, a plurality of relays connected to and energized by said AND circuits and a voltage dividing circuit having a resistor coupled to said source of D.C. current and adapted to pro-

duce step-down voltages at intermediate terminals provided on said resistor upon application of a D.C. current thereto, and contacts connected to said terminals, whereby predetermined voltages are selectively obtained by means of said contacts being actuated by said energized relays;

a voltage controlled variable frequency oscillator means connected to said contacts of said D.C. voltage generator for generating a bass tone signal proper for the detected chord, said bass tone signal being at a frequency determined by said D.C. voltage;

a rhythm pattern pulse generator means for generating pulses of predetermined rhythm patterns, and a tone gate means connected to said oscillator means and said pulse generator means for gating said generated bass tone signal in response to said pulses.

2. An automatic accompaniment device as claimed in claim 1 in which said voltage controlled variable frequency means comprises a first oscillator and a second oscillator, the first oscillator generating a bass tone signal having a frequency of the root note for the detected chord, the second oscillator operating simultaneously with the first oscillator and generating a base tone signal having a frequency of the fifth note for the detected chord, the first and the second oscillator being connected respectively to a pair of tone gates which gates the signals, applied thereto from the first and the second oscillator, in accordance with the rhythm pattern pulses from the rhythm pattern pulse generator.

3. An automatic accompaniment device instrument as claimed in claim 1 in which said variable frequency oscillator means comprises an astable multivibrator and a voltage amplifying circuit connected to said astable multivibrator.

4. In an electronic musical instrument having a plurality of key switches wherein actuation of each key switch acts to generate a different single note of a musical scale, and automatic accompanying device therefor, said device comprising:

a voltage means, said key switches being connected to said voltage means;

chord detector means coupled to said individual key switches for monitoring designated combinations of notes being played to detect the presence of different chords, said chord detecting means comprising a plurality of AND circuits connected to said key switches as chord detecting logics, said chord detector means providing an output indicative of said selected chord;

a D.C. voltage generator means coupled to said chord detector means for generating a D.C. voltage having a level representative of said detected chord, said D.C. voltage generator comprising a source of D.C. current, a plurality of relays connected to and energized by said AND circuits and a voltage dividing circuit having a resistor coupled to said source of D.C. current and adapted to produce step-down voltages at intermediate terminals provided on said resistor upon application of a D.C. current thereto, and contacts connected to said terminals, whereby predetermined voltages are selectively obtained by means of said contacts being actuated by said energized relays;

a voltage controlled variable frequency oscillator means connected to said contacts of said D.C. volt-

age generator for generating a bass tone signal proper for the detected chord, said bass tone signal being at a frequency determined by said D.C. voltage;

a rhythm pattern pulse generator means for generating pulses of predetermined rhythm patterns, and a tone gate means connected to said oscillator means and said pulse generator means for gating said generated bass tone signal in response to said pulses, and wherein said plurality of AND circuits 10 comprises a first and a second AND circuit group, the first AND circuit group being connected to said key switches which correspond to the notes of a chord thereby carrying out logical operation thereof, the second AND circuit group being connected to and operated by the output of the first AND circuit group and the outputs of the rhythm pattern pulse generator, and wherein said plurality of relays are connected to and energized by the second AND circuit group.

5. In an electronic musical instrument having a plurality of key switches wherein actuation of each key switch acts to generate a different single note of a musical scale, and automatic accompanying device therefor, said device comprising:

a voltage means, said key switches being connected to said voltage means; chord detector means coupled to said individual key switches for monitoring designated combinations of notes being played to detect the presence of different chords, said chord detecting means comprising a plurality of AND circuits connected to said key switches as chord detecting logics, said chord detector means providing an output indicative of said selected chords;

a D.C. voltage generator means coupled to said

chord detector means for generating a D.C. voltage having a level representative of said detected chord, said D.C. voltage generator comprising a source of D.C. current, a plurality of relays connected to and energized by said AND circuits, and a voltage dividing circuit having a resistor coupled to said source of D.C. current and adapted to produce step-down voltages at two groups of intermediate terminals provided on said resistor upon application of a D.C. current thereto, and contacts connected to said terminals, whereby predetermined voltages are selectively obtained by means of said contacts being actuated by said energized relays;

a voltage controlled variable frequency oscillator means for generating a bass tone signal proper for the detected chord, said bass tone signal being at a frequency determined by said D.C. voltage;

a rhythm pattern pulse generator means for generating pulses of predetermined rhythm patterns, and a tone gate means connected to said oscillator means and said pulse generator means for gating said generated bass tone signal in response to said pulses;

and wherein a voltage gate circuit is connected to said rhythm pattern pulse generator and said D.C. voltage generator, said gate circuit providing a gating operation which is carried out in accordance with the rhythm pattern pulses from said rhythm pattern pulse generator to thereby gate said D.C. voltage supplied from said D.C. voltage generator, said gate circuit further providing an output signal which is applied to the voltage controlled variable frequency oscillator means.
